METALWORKING TOOL

Russell D. Stephens, Detroit, Mich., assignor to
The Murray Corporation of America, Detroit,
Mich., a corporation of Delaware

Application September 23, 1942, Serial No. 459,417

9 Claims.

(Cl. 29—90)

This invention relates to methods and devices for burnishing and working metal, and particularly to a method and device for eliminating scratches from metal or other materials.

One application of the method and device of the present invention is that of dressing out scratch marks which are present in the sheets of metal employed for covering airplanes. Such sheets have a central core of aluminum alloy, for providing durability and strength, which is clad on both sides with pure aluminum, to prevent oxidation. When the surface of a sheet becomes scratched the core metal is exposed and subject to oxidation. To close the scratch marks the method and device of the present invention are employed to operate on the aluminum at the sides of the mark and to work it back into its original position in the base of the mark and into abutting sealing relation.

The method embodies the rotation of an eccentrically mounted segmental spherical tip as it is advanced along the scratch mark for urging the metal at the sides of the mark toward the bottom and center thereof. The mark becomes filled with the metal which is forced into such intimate physical engagement as to be in sealed relation. The tip is mounted on a shaft in slightly off-center relation to the axis of the shaft which is secured in a chuck on the end of an electric drill or other device which rotates the shaft and revolves the tip about the shaft axis. This produces the working of the metal, and its movement into the scratch, the sealing of the metal, and the polishing of the surface eliminates any appearance of the scratch after the operation.

Accordingly, the main objects of the invention are: to provide a tip having a segmental spherical surface on a shaft having its axis disposed in offset relation to that of the tip for operation on scratch marks in the surface of a material; to provide a method for eliminating scratch marks from material which embodies the working of the material on each side of the marks for filling in the mark and sealing the abutted material; to provide a tool for rotating a shaft having a tip with a curved working surface, the axis of which is offset from the axis of the shaft for working the metal on either side of a scratch mark, and in general, to provide a method and device for working metal which is simple in construction, positive in operation, and economical of manufacture.

Other objects and features of novelty of this invention will be either specifically pointed out,

or will become apparent when referring, for a better understanding of the invention, to the following description taken in conjunction with the accompanying drawing, wherein:

5 Figure 1 is a view, in elevation, of a driving tool and a scratch eliminating tip embodying features of the invention;

Fig. 2 is an enlarged broken view of the tip illustrated on the tool in Fig. 1; and

10 Fig. 3 is a view of the tip illustrated in Fig. 2, and a sheet of material having a scratch upon which the tip is operating.

In Fig. 1 an electric drill 5 is illustrated, of conventional form, having a chuck 6 which is driven in rotation thereby. The chuck supports and drives a shaft 7 having a tip 8, the axis 9 of which is offset from the axis 11 of the shaft. As the shaft 7 rotates the tip 8 will revolve about the axis of the shaft and the segmental spherical surface 12 thereof will work the metal on both sides of the scratch mark toward the base and center thereof.

In Fig. 3, the tip 8 is illustrated as having the segmental spherical surface 12 disposed along a slot 13 in a sheet of material 14. The tip will operate on the metal on each side of the scratch mark to work the metal into the base of the mark and into abutting sealing relation. The continuous rotation of the shaft and the revolving tip will polish the surface after the scratch mark is filled and sealed. The tool is preferably slowly moved back and forth along the mark as the operation progresses. The base of the mark is filled with material as the material of the adjacent walls is forced into sealing relation. The further operation of the tool will polish the surface of the metal and the scratch mark will be quickly eliminated.

The device and method eliminates the necessity of scrapping stampings and sub-assemblies of airplanes, and the substitution of parts for those having scratch marks on their surfaces. A very short time is all that is required to seal the mark and polish the surface of the material. The Alclad sheets have an oxidizable core material which will be exposed to the air when the outer aluminum coating is cut through. The aluminum on both sides of the scratch mark is moved into the mark and into abutting sealed relation, and the core material is completely protected against oxidation.

What is claimed is:

1. The method of eliminating scratch marks from the surface of a material which includes the steps of, working the metal on both sides of

the scratch mark into the base of the mark and into abutting relation by a circular motion of a burnishing element about an axis disposed substantially normal to the surface of the material.

2. The method of eliminating scratches from the surface of material which includes the steps of, rotating a point of engagement of a tool with the metal on both sides of the scratch in a circle of a diameter greater than the width of the scratch with the axis of the circle disposed normal to the scratch for simultaneously drawing the metal on both sides thereof into the base of the scratch and into intimate physical engagement for sealing the scratch.

3. The method of eliminating scratches from the surface of material which includes the steps of, rotating a point of engagement of a tool with the metal on both sides of the scratch in a circle of a diameter greater than the width of the scratch with the axis of the circle disposed normal to the scratch for simultaneously drawing the metal on both sides thereof into the base of the scratch and into intimate physical engagement for sealing the scratch, and polishing the surface of the filled scratch by the continued operation of said tool.

4. A device for eliminating scratches from the surface of a material which includes, a tip having a segmental spherical surface, a shaft of less diameter than said tip supporting said tip with its axis offset from the axis of the tip, and means for driving said shaft in rotation.

5. A tool for eliminating scratch marks from the surface of a material which includes, a shaft, a tip of greater diameter than said shaft disposed on the end of the shaft with its axis offset from

that of the shaft, and a rounded face concentric with the axis of the tip disposed on the end thereof opposite to that from which the shaft extends.

6. A tool for eliminating scratch marks from the surface of a material which includes, a shaft, a tip of greater diameter than said shaft disposed on the end of the shaft with its axis offset from that of the shaft, a rounded face concentric with the axis of the tip disposed on the end thereof opposite to that from which the shaft extends, and driving means for rotating said shaft.

7. A device for eliminating scratch marks from the surface of a material which includes, a tip having rounded surface on the axis thereof, a shaft of less diameter than said tip extending from the opposite side of the tip from that having the rounded surface, the axes of said shaft and tip being offset, and driving means for rotating said shaft.

8. The method of eliminating scratch marks from an aluminum clad sheet of material which includes the steps of, simultaneously moving the aluminum at both sides of the scratch mark toward the center of the mark to fill the mark by movements laterally across the mark, and physically bonding the aluminum to form a seal for the material.

9. The method of eliminating scratch marks from an aluminum clad sheet of material which includes the steps of, simultaneously moving the aluminum together from both sides of the scratch mark by movements laterally across the mark to fill the mark, physically bonding the aluminum to form a seal for the material, and polishing the surface of the bonded aluminum.
